HOUSE DRAIN FITTING

Silvestro Cavalieri, Chicago, Ill.

Application June 6, 1945, Serial No. 597,891

9 Claims. (Cl. 182—31)

1

This invention relates to the type of house drain fittings which are placed in the basement and like floors of buildings, opening on a level with the floors, and provided with sealing gaskets, orificed drain grids or strainer plates, and with removable closure heads.

A fitting of this type is disclosed in my prior patent, No. 1,812,583, issued June 30, 1931. This prior fitting is used in combination with a drainpipe having an expanded annular inlet head arranged on a level with the floor surface. A circular drain fixture is disposed within the expanded inlet head of the drainpipe and firmly cemented in place therewith. The drain fixture is provided with a strainer plate and with a removable cover therefor. Draining of water which accumulates in the place equipped with the fitting, for example, in the basement, is effected through the strainer plate upon removal of the cover. Among the advantages of the prior fitting may be mentioned its structural simplicity and ease of installation.

The present invention preserves and retains these advantages and introduces a number of features which are valuable from the standpoint of manufacture as well as installation and safe and efficient operation of the fitting. Some of the objects and features of the invention are noted below.

One object of the invention is concerned with the provision of an improved drain fitting comprising a tubular generally circular shell forming a downwardly extending skirt or apron which is disposed over the drainpipe and cemented in place therewith, and having an upwardly extending generally circular housing for receiving a strainer plate, a gasket, and a removable cover.

The novel fitting can be employed with drainpipes of different diameters, thus contributing to the standardization of such fittings and reducing the number of sizes which must be kept in stock.

The new fitting provides a relatively large bonding area as compared with previously known structures of this type, and thus assures secure cementing in place.

Another object of the invention is realized by the provision of a vent pipe attached to the removable cover of the fitting for the purpose of relieving internal pressure, thus eliminating danger of damage to the fitting or to the floor, or both, as well as expenses for repair and inconvenience to the property owner.

These and additional objects and features will be brought out in the course of the detailed

2

description which is rendered below with reference to the accompanying drawings. In these drawings,

Fig. 1 represents an embodiment of the new fitting in elevation;

Fig. 2 illustrates a top view of Fig. 1;

Fig. 3 is a cross-sectional view of the fitting and the drainpipe taken approximately along lines 3—3 of Fig. 2; and

Fig. 4 shows a fragmentary view of the housing and cover approximately along the sectional lines 4—4 in Fig. 2.

Like parts are identified by like reference numerals throughout the drawings.

Reference numeral 11 indicates the upper end of a drainpipe which may connect, for example, with the sewer. The drainpipe is sunk in the floor 13 and is provided with a flange 12 which may be part of the drainpipe or may be attached to it in any approved and suitable manner. The fitting may be provided for a drainpipe of a certain diameter, but may also be used in connection with drainpipes of smaller diameter. In the first case, the flange 12 may be part of the drainpipe, and in the latter case the flange may be suitably attached to it. The drainpipe with its flange extends through the cement 13, forming the floor, near the upper surface thereof.

The new drain fitting is made in the form of a tubular shell comprising a lower generally circular section 14 depending downwardly in the form of a skirt or apron and a section 15 forming a housing and extending upwardly therefrom. The two sections form a central annular portion 16, providing at 17 a seat for engagement with the flange 12 of the drainpipe. The upper section 15 of the fitting comprises the generally circular portion 18 which is of smaller diameter than the apron 14 and is provided with two oppositely disposed radially extending enlargements 19 and 20. At the juncture of the upper and lower sections of the fitting is formed the shoulder 21. The fitting is placed on the drainpipe, as illustrated in Fig. 3, with the flange 12 engaging the seat 17, and is cemented in place with the drainpipe. If desired or necessary, a washer-like gasket or gaskets may be inserted between the flange 12 of the drainpipe and the seat 17. The installation is thus benefited and the alignment with the floor surface is facilitated, the annular seat 17 furnishing a spacer means to align the upper edge of the fitting with the surface of the floor. The seat 17 also centers the fitting properly with respect to the drainpipe. It will be observed that the depending por-

tion of the fitting forming the skirt or apron 14 tapers inwardly, as shown, so as to facilitate the insertion and placement of the structure. The upper end of the housing section 15 of the fitting is disposed on a level with the surface of the cement floor 13. The fitting presents a large bonding area. Its displacement upwardly is prevented by the shoulder 21, while its angular placement is secured by the enlargements 19 and 20 radially extending from the upper housing section 15.

An orificed strainer plate or grid having ribs such as indicated at 22 is placed in the shallow circular well formed by the central section 16 of the fixture. A suitable gasket 23 is placed above the grid into the shallow annular rim formed above the well containing the strainer plate or grid.

The radially projecting enlargements 19 and 20 are provided with openings 24 and 25, respectively, for the insertion of the projections or lugs 26 and 27, respectively, which extend radially from the edge of the circular cover 28. These lugs or projections 26 and 27 are tapered, as particularly shown in Fig. 4, for locking engagement with the tapered under side of the locking slots such as 29. The action of the lugs 26 and 27 with respect to the locking slots is well known from so-called bayonet joints.

The cover 28 may be a cast structure and, similarly, the fitting may be a cast structure. The cover 28 may be provided with downwardly extending, hollowed-cut portions, indicated in Fig. 2 at 30 and 31, for the purpose of forming radial ribs 32 and 33 to facilitate the rotation required incident to insertion and removal of the cover.

The vent pipe 33 may be screwed into the cover, as shown in Fig. 3, and may be secured thereto by means of a nut 34 and a washer 35. The pipe extends upwardly and may be furnished in a length required for any given conditions indicated by experience. For example, if the highest level to which a basement may be flooded is two feet, the vent pipe required will measure just a little over two feet; or if experience indicates that back pressure in the sewer may lift the contents of the drainpipe by say, two feet, a vent pipe measuring a little over two feet in length will be sufficient. The upper free end of the vent pipe 33 may be squared, as indicated at 36, for the purpose of operating the lid or cover 28 by means of a wrench or the like, thus eliminating the necessity of removing the lid for drainage by the operation of the cover itself.

The operation of the drain fitting will be apparent from the above description, but may be summarized as follows:

Once the fitting is put in place, as indicated in the figures, it is ready for operation. Internal pressure is relieved through the vent pipe 33 and the drain-pipe contents may rise in this vent pipe. Damage to the floor or to the fitting, or to both, which may otherwise result from pressure in the sewer system, is thus avoided. Water may accumulate in the basement above the fixture and around the vent pipe 33. When draining is desired, the lid or cover 28 is removed by twisting it in counter-clockwise direction, as seen in Fig. 2, to remove the lugs 26 and 27 from engagement with their locking slots in the enlargements 19 and 20, whereupon the lid and the vent pipe are lifted out. The water then flows into the drainpipe 11 through the apertures between the ribs 22 in the strainer plate or

grid. Debris collecting above the grid may be removed and the lid or cover 28 may then again be put in place by first inserting the lugs 26 and 27 into the openings 24 and 25, and then turning the lid or cover in clockwise direction, as seen in Fig. 2, so as to lock the lugs 26 and 27 in their respective slots such as 29, shown in Fig. 4.

Changes may be made within the spirit and scope of the following claims which define what is believed to be new and desired to have protected by Letters Patent of the United States.

I claim:

1. A house drain fitting of the class described, for coaction with a drainpipe sunk in the floor, comprising a generally circular tubular shell having a downwardly depending generally circular skirt disposed around the upper end of said drainpipe and radially spaced therefrom and a tubular generally circular housing of smaller diameter than said skirt extending upwardly from said skirt and forming a peripheral annular shoulder therewith for anchoring said shell against axial upward displacement, the upper edge of said housing being level with the floor surface, said skirt tapering downwardly and inwardly to facilitate the placing thereof with respect to said drainpipe, and said housing being provided with enlargements radially outwardly projecting therefrom to secure the fitting against angular displacement relative to said drainpipe.

2. The combination and structure defined in claim 1, together with an annular radially inwardly projecting flange in said fitting forming an axially recessed annular seat for centering engagement with said drainpipe.

3. The combination and structure defined in claim 1, together with an annular radially inwardly projecting flange in said fitting forming an annular recess for receiving a strainer plate and also forming an annular shoulder for receiving a gasket, and a cover for attachment to said housing in engagement with said gasket.

4. The combination and structure defined in claim 1, together with an annular radially inwardly projecting flange in said fitting forming an annular recess for receiving a strainer plate and also forming an annular shoulder for receiving a gasket, a cover for attachment to said housing in engagement with said gasket, and means in the enlargements carried by said housing for securing said cover.

5. The combination and structure defined in claim 1, together with an annular radially inwardly projecting flange in said fitting forming an annular recess for receiving a strainer plate and also forming an annular shoulder for receiving a gasket, a cover for attachment to said housing in engagement with said gasket, said cover being provided with lugs radially extending therefrom, and means in the enlargements carried by said housing for securing said lugs to secure said cover.

6. In a house drain of the class described, the combination of a drainpipe sunk in the floor, with a tubular generally circular drain fitting surrounding the upper end of said drainpipe below the floor level, and an annular radially inwardly projecting flange forming in said fitting spacer means for engagement with the drainpipe to align the upper edge of the fitting with the surface of the floor.

7. In a house drain of the class described, the combination of a drainpipe sunk in the floor, such as a cement floor, with a fitting sunk into and anchored in said floor in coacting relation-

ship with said drainpipe and with its upper edge substantially level with the floor, said fitting consisting of a unitary generally circular tubular shell comprising a lower tubular downwardly and inwardly tapering portion and an upper tubular housing portion of smaller diameter than said lower portion to form an outer annular peripherally extending shoulder which anchors the fitting in the floor against axial upward displacement, the downward and inward taper of said lower portion of the shell facilitating the placing of said fitting relative to said drainpipe, and a plurality of enlargements projecting radially outwardly from said upper housing portion of the shell for anchoring said fitting in said floor against angular displacement relative thereto.

8. The structure and combination defined in claim 7, together with a cover for said fitting, lug means extending radially from said cover, and a recess formed in each of said radially extending enlargements of said housing portion for receiving an associated lug means of said cover for the purpose of securing said cover on said fitting.

9. The structure and combination defined in claim 7, together with an annular flange projecting radially inwardly from the inner wall of said shell, said flange forming a plurality of an-

nular recesses, namely, (1) an annular downwardly facing recess for engagement with the top of said drainpipe, whereby said fitting is centered on the drain pipe and its upper edge is aligned with the floor lever, (2) an annular intermediate upwardly facing recess for receiving a strainer, and (3) an annular upwardly facing top recess of larger diameter than said intermediate recess for receiving an annular gasket and a cover in sealing engagement with such gasket, a plurality of lug means forming part of said cover and radially projecting therefrom, and a recess formed in each of said radially extending enlargements of said housing portion for receiving an associated lug means of said cover for the purpose of securing the cover on said fitting.
